DESIGN FOR A SMOKING PIPE

Giovanni Trasso, Hanford, Calif.

Application January 8, 1945, Serial No. 117,333

Term of patent 3½ years

(Cl. D85—8)

To all whom it may concern:

Be it known that I, Giovanni Trasso, a citizen of the United States, residing at Hanford, in the county of Kings and State of California, have invented a new, original, and ornamental Design for a Smoking Pipe, of which the following is a specification, reference being had to the accompanying drawing, forming a part thereof.

I claim:

The ornamental design for a smoking pipe, as shown.

GIOVANNI TRASSO.
